UNITED STATES PATENT OFFICE.

LOUIS W. GREVE, OF CLEVELAND, OHIO, ASSIGNOR TO THE CHAMPION MACHINE & FORGING COMPANY, OF CLEVELAND, OHIO, A CORPORATION OF OHIO.

AUTOMATIC FORGING MACHINE.

Application filed January 14, 1924. Serial No. 686,034.

This invention relates to an automatic forging machine, and is an improvement over the construction illustrated in my prior application, Serial No. 673,550, filed November 8, 1923.

In my application above referred to, I have disclosed a forging machine or manipulator which does away with the hand manipulation of blanks under a hammer, this machine being associated with a furnace and a drop hammer with which the forging is done, and serving to take a heated blank from the furnace, convey and move it under the hammer, to control the hammer and to move the blank about between the usual dies of the hammer, and to otherwise perform automatically movements and acts done manually to obtain finished forgings so as to dispense with considerable skilled labor now required.

The machine formed in accordance with the present invention is of the general type of that illustrated in my prior application, the principal objects of the present invention being to simplify and to reduce the weight and working parts of the machine shown in my prior application referred to.

The invention may be briefly summarized as consisting in certain novel details of construction and combinations and arrangements of parts which will be described in the specification and pointed out in the appended claims.

In the accompanying sheets of drawings illustrating the invention in its preferred form, Fig. 1 is a top plan view of the machine showing partly in section and partly in elevation a portion of the drop hammer and the delivery member of the heated blanks passing from the furnace; Fig. 2 is a side view of the same; Fig. 3 is an end view looking toward the right of Fig. 2; Fig. 4 is a sectional view substantially along the line 4—4 of Fig. 2, looking in the direction indicated by the arrows; Fig. 5 is an enlarged view partly in side elevation and partly in section with the machine viewed as in Fig. 2; Fig. 6 is an enlarged transverse sectional view substantially along the line 6—6 of Fig. 1, looking in the direction indicated by the arrows; Fig. 7 is a plan view and Fig. 8 is an end view of a support for the drum controlled slides; Fig. 9 is a plan view; Fig. 10 is an end view of one of a series of slides; Figs. 11 and 12 are views corresponding to Figs. 9 and 10, showing another form of slide utilized; Fig. 13 is a view partly in side elevation and partly in section showing the manipulator arm removed from the machine; Fig. 14 is an end view of Fig. 13, looking toward the right of Fig. 13, the lower part of the arm support being removed; and Fig. 15 is an end view of the arm shown in Fig. 13, looking toward the left of Fig. 13.

cated by the arrows; Fig. 7 is a plan view and Fig. 8 is an end view of a support for the drum controlled slides; Fig. 9 is a plan view; Fig. 10 is an end view of one of a series of slides; Figs. 11 and 12 are views corresponding to Figs. 9 and 10, showing another form of slide utilized; Fig. 13 is a view partly in side elevation and partly in section showing the manipulator arm removed from the machine; Fig. 14 is an end view of Fig. 13, looking toward the right of Fig. 13, the lower part of the arm support being removed; and Fig. 15 is an end view of the arm shown in Fig. 13, looking toward the left of Fig. 13.

My improved machine for manipulating the blanks from which the forgings are to be made, is used in connection with a hammer, which as in my prior case may be and preferably is a drop hammer, of usual construction, except for certain control features to be referred to. A portion of the hammer is shown at 10 in Figs. 1, 2 and 3. Likewise, the machine is associated with a furnace of suitable construction preferably having an automatic feed for the blanks, but the details of the furnace are not material to the present invention, a portion of the furnace being shown at 11 in Fig. 2.

In my prior application the furnace was located at one side of the hammer, and the blank manipulating machine was so constructed that the manipulator arm not only was capable of moving laterally with respect to the hammer, and toward and from the hammer, but it was mounted on a turret which enabled it to have a rotary movement through a suitable arc, a combination of straight line and rotary movements being given to the arm to cause the arm to carry the blank from the furnace to the hammer.

The present machine is so constructed as to do away with the necessity of the rotary movement of the arm, though the lateral and front and rear motions are retained. To permit this, the furnace is preferably arranged at the rear of the hammer, as indicated in Fig. 2, and there is provided a delivery member for the heated blanks, by or through which the heated blanks may be

65

70

75

80

85

90

100

5 moved forwardly from the furnace to a point at or near the front of the hammer where the blanks may one at a time be gripped by the jaws of the manipulator arm. This delivery member as here shown is in the form of a trough 12 (see particularly Fig. 1), which trough as here shown, extends forwardly between the stationary die 13 of the hammer and one of the side housings thereof. Any 10 suitable means, preferably automatically operated, may be employed for moving the blanks forwardly along this trough to the delivery point or to the jaws of the manipulator arm.

15 At this point it might be mentioned that in this machine, as in my prior machine, the lateral and front to rear motions of the manipulator arm are obtained through the provision of two carriages, one carrying the arm 20 and movable in one direction, and mounted on a second carriage mounted on the frame or base of the machine and movable in a direction at right angles to the first-named carriage. The control of these carriages and 25 other parts of my prior construction was obtained through cam actuated levers and a pair of drums having cam grooves, all this control mechanism being mounted on the upper carriage and movable therewith. It 30 is a feature of the present machine that the control mechanism is not only simplified with respect to that of my prior machine, but it is mounted in the stationary part of the machine, enabling the machine to be made smaller and lighter, and requiring less power 35 to actuate the moving parts.

As clearly shown in Figs. 1 and 2, the blank manipulating machine is located in front of the hammer 10. The machine includes a stationary frame or base 14, in the lower part of which the major portion of the control mechanism is located, as is apparent from an inspection of the drawings, particularly Figs. 2 and 3.

45 Supported at the upper part of the frame 14 is a carriage 15 which may be termed the lower carriage, which in this instance moves laterally in front of the hammer. This carriage is supported on wheels 16 engaging trackways on the frame, and it is moved along the frame by pinions 17 on a front-to-rear shaft 18 extending along the lower part of the carriage 15, these pinions engaging racks 19 (see particularly Fig. 2) carried on the under sides of gibs 20 secured to the front and rear ends of the frame in position to act as guides for the carriage 15. The drive for shaft 18 will be explained presently.

50 Mounted on the carriage 15 to travel toward and from the hammer is the upper carriage 21 having wheels 22 engaging trackways of the lower carriage 15 (see particularly Fig. 4). The upper carriage is moved forwardly and rearwardly by pinions 23 on a shaft 24, the pinions 23 engaging racks 25

secured to the under sides of gibs 26 secured to the sides of the upper carriage 15, as clearly shown in Fig. 4.

55 The upper carriage 21 carries the manipulator arm 27, the construction of which is like that shown in my prior application, the arm having at its rear end a depending supporting portion 28 fitting within a receiving part 29 depending from the upper carriage 21. The supporting part 28 of the arm is 70 adapted to slide up and down in the receiving part 29 of the carriage, but does not rotate therein as in my prior application.

60 The power for operating the main parts of the machine is obtained from a motor, preferably an electric motor, not here shown, and adapted to be supported along or on one side of the base. I have illustrated in Fig. 6 at 30, a portion of the motor shaft, this shaft being connected by spur gearing designated 85 as a whole by the reference character 31, and located just inside the frame or base, as clearly shown in Fig. 6, to a short shaft carrying one of the spur gears, and a bevel gear 32 which meshes with a bevel gear 33 on a 90 main power shaft 34 extending from front to rear near one side and near the bottom of the frame or base 14. The power shaft 34 is adapted to be continuously driven, though it may be stopped through the medium of a 95 clutch 35 (see Fig. 1) adapted to be shifted by a yoke 36 operated by an air cylinder 37 controlled by an air valve 38 supported on the front part of the frame and having an operating handle 38a to be referred presently. 100

105 The main power shaft 34 is connected by an inclined shaft 39 and by suitable bevel gearing to a shaft 40 of a cam drum 41 supported in bearings of the frame, which cam drum automatically controls the movement of the main parts of the machine to cause it to function in the manner previously stated and as will be subsequently described more at length. It is to be noted that the controlling drum 41 is supported by and within the frame or base independently of either carriage. 110

115 This drum has in this instance six cam grooves 42 which are engaged by rollers 43 carried by slides 44 arranged in two slide-ways 45 of a stationary slide support 46, (see particularly Figs. 6, 7 and 8), these slides being adapted to actuate clutches and valves through which the machine is controlled. In this instance, for convenience, the slides are arranged in two guideways disposed in a diagonal plane, each slideway being adapted to receive three of the slides. The three in the upper slideway have downwardly projecting lugs or extensions 44a for carrying the rollers 43, and upwardly projecting bosses 44b to which the corresponding slide actuated parts in the form of links or levers are adapted to be connected. The details of these slides are shown in Figs. 11 125 130

and 12. The slides in the lower guideway have upwardly projecting lugs or extensions 44^c for the rollers 43, and downwardly projecting lugs 44^d to which the appropriate 5 slide actuated parts are adapted to be connected, these being shown in detail in Figs. 10 and 11.

Power is derived from shaft 34 to shift both carriages. The lower carriage 15 is 10 driven through shafts and gears located near the rear part of the frame and illustrated in Figs. 2, 3 and 5. The driving connection includes bevel gears 47, either of which is adapted to be clutched to the power shaft 34 15 through the medium of two clutches 48 controlled by a double clutch yoke 49. These bevel gears 47 are adapted to alternately drive in one direction or another, a bevel gear 50 on a short vertical shaft 51 supported by the frame of the machine and connected by bevel gear 52 to a shaft 53 which is above and at right angles to the main power shaft 34 and supported in bearings 20 near the rear end of the frame. This shaft 53 carries a spur pinion 54 which is splined on the shaft or has a sliding connection thereon. That is to say, it is rotated by the shaft and may move lengthwise of it. This pinion 54 forms a part of the gear train 25 movable with the lower carriage 15, the pinion being shifted along the shaft by an arm 55 extending downward from the carriage, this arm being best shown in Figs. 3 and 5. The gear train of which the spur pinion 54 30 is a part, includes two additional spur pinions, the upper one of which is on a short shaft 56, shown by dotted lines in the drawings, which shaft is supported by the carriage 15, and is connected by bevel gearing 57 to shaft 18, previously referred to, carrying the pinions 17 engaging the racks 19 35 of the frame. Thus it will be seen that the lower carriage 15 and all parts supported by it, including the upper carriage and the manipulator arm, may be moved laterally across the front of the drop hammer in either direction, and can be stopped in any position by actuating the clutches 48. The clutch yoke 49 is adapted to be shifted by a lever 58 shown by dotted lines in Fig. 1, and by a link 59 to one of the cam actuated slides 44.

In a somewhat similar manner the upper carriage is moved back and forth toward and from the hammer by gears and shafts carried in part by the stationary frame or base, in part by the lower carriage 15, and in part by the upper carriage. The driving connections between the main power shaft and the upper carriage are as follows: Near the 40 front end of the main power shaft 34 are two bevel gears 60 adapted to be separately clutched to the shaft 34 by clutches 61, in turn adapted to be actuated by a double clutch yoke 62 connected by a link 63 (see 45 particularly Fig. 1) to one of the cam actu-

ated slides 44. These bevel gears are adapted to rotate a bevel gear 64 on a short vertical shaft 65 connected by bevel gears 66 to a horizontal shaft 67 supported in bearings in the front part of the frame 14. Splined on 70 this shaft 67 is a spur pinion 68 adapted to be moved along the shaft by a depending arm 69 of the lower carriage 15. This pinion 68 forms a part of a gear train movable with the lower carriage, as clearly shown in Fig. 75 4, this gear train including additional spur gears, the upper of which is mounted on a short shaft 70 located on the lower side of the carriage 15 and supported thereby. This shaft which is immediately above shaft 67, is 80 connected by bevel gears 71 to a relatively long shaft 72, also supported on the lower side of the carriage 15 but at right angles to the shafts 67 and 70. By reference particularly to Fig. 5, it will be seen that this shaft 85 72 carries a spur pinion 73 which is splined to and slidable along shaft 72, it being moved lengthwise of the latter by an arm 74 extending down from the lower side of the upper carriage 21. This splined pinion 73 forms 90 a part of a spur gear train carried by the upper carriage 21, the upper pinion or gear of which is on a short shaft 75 connected by bevel gearing 76 to shaft 24 of the upper carriage provided with the pinions 23 which 95 engage the racks 25.

Thus it will be seen that with the clutches 48 in neutral position, the upper carriage with the manipulator arm will be moved laterally with the lower carriage when the lower carriage is moved in either direction by having one of the clutches 61 engaged, and by actuating the clutches 48 the upper carriage may be moved forwardly or rearwardly on the lower carriage either while the latter 100 is stationary or moving. An auxiliary clutch 77 on the short vertical shaft 65, and shown in both Figs. 4 and 6 is utilized also at times for the control of the upper carriage. This clutch is operated by a yoke 78, adapted to 105 be shifted by an air cylinder 79 shown in Figs. 1, 4 and 6, the plunger or piston in this cylinder being adapted to be operated to disengage clutch 77 by an air valve 80 mounted on the front part of the hammer, as indicated 110 in Fig. 1. The function of this will be referred to presently. It will be understood, of course, that to move the upper carriage forwardly and rearwardly by the actuation of the clutches 61, the clutch 77 must be engaged, and that when this clutch 77 is disengaged, the movement of the upper carriage 115 at once stops irrespective of the positions of the clutches 61.

It will be seen that the cam drum through 120 its actuation of the slides connected to the clutches 48 and 61 will automatically cause the manipulator arm, through suitable movements imparted to the two carriages, to be given lateral or forward or rearward move- 125 130

ments either separately or in combination, and may stop and start either or both these movements at predetermined times.

The construction of the manipulator arm is identical with that illustrated in my prior application, and will therefore be here described quite briefly. The arm is provided at its forward end with a pair of pivoted jaws or tongs 81 adapted to be closed and opened by the movement of a piston in an air cylinder 82 carried by the forward part of the arm to grasp and release the heated blanks, one of which is shown at 83 in the trough 12 of Fig. 1.

As in my prior application, the arm is composed of several tubes, part hinged and part telescopically arranged. It includes a rear tube 84, journaled in a horizontal tubular extension 85 at the top of the arm support 28. The inner or rear tube 84 carries at the center a gear 86 by which the entire arm may be turned about its longitudinal axis through an arc of 90° in either direction, the gear 86 being engaged by a vertically movable rack 87 adapted to be actuated by an air cylinder 88 located in the arm support 28 as indicated in Fig. 15.

The forward end of rear tube 84 is connected by a hinge 89 to a tube 90 in which is received an inner tube 91 slidable in the outer tube, but normally held retracted in the latter by a spring 92 or equivalent device. These two telescopic tubes are provided to allow the arm to be elongated in the event a forging sticks to the upper die of the drop hammer. One of these tubes has a slot 93 receiving a pin 94 on the other tube, the pin and slot connection permitting the telescopic movement and serving as a guide to prevent one tube rotating in the other. Secured to the forward end of the inner tube 91 is a short filler tube 95 to which is secured a forwardly projecting tube 96 constituting in effect an extension of the inner tube 91, and telescopically arranged in tube 96 is a forward tube 97 carrying the jaws 81. These two telescopic tubes 96 and 97 are provided to permit the shortening of the arm as the blank elongates while being forged, a relative movement between these tubes of a definite amount being permitted by a pin and slot connection indicated at 98 in Fig. 13. The forwardmost tube 97 is normally held in its outermost position by a spring 99, but it may move back or inward against the action of the equivalent of a friction brake 100 engaging the rear part of the inner surface of the tube 97, this brake being controlled as in my prior application by the movement of a piston in an air cylinder 101 located in tube 91.

As in the manipulator arm of my prior application, if a forging sticks to the upper die of the hammer so that the forward end of the arm is carried upwardly, the tube 90

while moving upwardly about the axis of hinge 89 engages and rocks a bell-crank arm 102 which actuates an air valve 103 which admits air to the top of a cylinder 104 carried by and extending down in the arm support 28 so as to cause the entire arm to be moved upward, this cylinder containing a piston 105 on a fixed rod 106 projecting up from the bottom of the receiving part 29 in which the arm support 28 is slidingly received. When the tube 90 again comes into alignment or substantial alignment with the rear tube 84 the air valve 103 is automatically reversed, again allowing the arm support 28 to slide down in the receiving part 29.

The supply of air to the cylinder which actuates the jaws or tongs 81, also to the cylinder 101 which controls the friction brake 100 in the manipulator arm, and also to the cylinder which moves the rack to rotate the arm, is controlled by valves supported in a stationary position in the frame or base and operated by certain of the cam actuated slides 44. These three valves, and a fourth valve, which at certain points in the cycle of operations controls the hammer, are all indicated in Fig. 1. The valve which controls the supply of air to the tong operating cylinder is shown at 107, the handle for this valve being connected by a link 108 to a bell crank 109, in turn connected by a link 110 to a lever 111 connected to one of the cam actuated slides 44. The arm which controls the supply of air to the cylinder 101 which actuates the brake 100 in the manipulator arm is shown at 112, the handle of this valve being connected by a link 113 to a bell crank 114, in turn connected by a link 115 to a lever 116 which is connected to another of the slides 44. The valve which controls the supply of air to the cylinder for actuating the rack 87 to rotate the manipulator arm is shown at 117, the handle of this valve being connected by a link 118 to a bell crank 119, in turn connected by a link 120 to a lever 121 connected to another of the cam actuated slides 44.

The fourth valve referred to for controlling the operation of the hammer is shown at 122, the handle of this valve being connected by a link 123 to a bell crank 124 in turn connected by a link 125 to a lever 126 connected to another cam actuated slide 44.

Flexible tubes connect all these valves to the moving parts, the tubes for supplying air to opposite ends of the cylinders 82 and 101 in the manipulator arm extending through the arm from its inner or rear end, as indicated particularly in Figs. 13 and 14.

The hammer herein illustrated is provided with a foot-board, here designated 127, which foot-board is ordinarily depressed by the foot of the operator when he desires the hammer to drop to deliver a forging blow to a blank on the lower die 13 of the

hammer. In this instance, as in my prior application, the foot-board is actuated by an air cylinder 128 and its plunger, indicated at 128 in Figs. 1 and 2, this air cylinder being supported on the lower part of the base of the hammer directly above the foot-board. The supply of air to the cylinder 128 is controlled at times by valve 80, referred to in the earlier part of this description, and 10 at times by the valve 122, which is operated by one of the cam actuated slides as explained above. The manner and times in which these valves are operated will be explained presently in describing the operation 15 of the machine.

To stop the hammer when it goes up after delivering the forging blow, I provide as in my prior application, an air valve 129 on the housing of the hammer, which valve is 20 turned by a ratchet device 130 operated by an adjustable stop 131 of the usual operating rod 131^a with which drop hammers are provided, the function of the valve being to admit air to the lower part of cylinder 25 128 so as to lift the plunger from the foot-board and thereby cause the hammer to be stopped in its uppermost position precisely as when the operator removes his foot from the foot-board as these hammers are ordinarily 30 operated. This valve 129 also reverses the air in clutch operating cylinder 79 allowing clutch 77 to reengage so that the upper carriage may be moved back and forth by the cam actuated clutches 48.

35 I prefer to provide also, as in my prior construction, means for lifting the manipulator arm slightly after each blow is delivered to the blank by the hammer so as to lift the blank from the die impression of the lower die to facilitate the lateral movement of the arm and blank to the next die impression. This is preferably accomplished, as in my prior application, by a small air cylinder which is indicated at 133 in Fig. 3, 40 this air cylinder being located in and secured to the inner side of the depending portion 28 of the arm and having a piston and a plunger adapted to engage a plate 134 constituting the bottom of the depending part 29 of the upper carriage which receives the part 28 of the arm. As in my prior application, air is supplied to this cylinder to actuate the same when the hammer goes up through the medium of a valve 45 135 supported on the hammer and operated by a second stop 136 on the operating rod 131^a. (See Fig. 3.)

The operation of the machine is as follows: Assuming that there is a proper feed 50 of blanks through the chute 12, and assuming that the manipulator arm is in position A (Fig. 1) in line with the feed of blanks, air is then supplied to the cylinder so as to actuate the piston which controls the jaws 55 or tongs which are thus caused to grip the

blank at one end, this valve being controlled by one of the cam actuated slides. Then the upper carriage is moved rearwardly and the lower carriage is then moved laterally and then the upper carriage is moved forwardly again so as to bring the blank into position B over the break-down die impression 13^a of the lower die 13 of the hammer, the movement of the carriages necessary to bring this about being controlled by the cam actuated slides. As the blank is moved forwardly in position B it strikes and shifts a lever 132, and this operates valve 80, causing the disengagement 75 of clutch 77, stopping the forward movement of the slide and blank. Likewise it admits air to the cylinder 128 controlling the hammer. The hammer now descends, delivers a blow to the blank in position B and rises and stops. Thereupon the lower carriage is actuated so as to move the blank to position C (Fig. 1) with the blank over the roughing out die 13^b. Then the hammer again drops, movement of the hammer now being controlled by the cam actuated valve 80 85 122. Then the lower carriage is moved laterally to bring the blank to position D with the blank over the finishing die impression 13^c. After a forging blow is delivered in the same manner as previously described, 90 the lower carriage is moved laterally to bring the blank to position E over the cut-off device 13^d, and when the hammer again descends through the actuation of the valve 122, the finished forging is cut off the 95 blank.

Assuming that two forgings are to be made from the blank, as is preferred, the sequence of operations above described is repeated, the blank being moved first to 100 position B, and moved forwardly until the end of the blank strikes control lever 132, causing the stopping of the forward movement and the operation of the hammer, after which the blank being moved successively to positions C, D and E.

105 It might be here stated that when the manipulator arm returns again to position B, the control lever 132 is returned to the position shown in Fig. 1, and this can be 110 accomplished by any suitable part traveling laterally with the lower carriage. In this instance the lower carriage is provided for this purpose with a forwardly projecting arm 132^a carrying at its outer end a 115 pivoted finger 132^b, free to move in one direction only from normal position in which it is held by a spring. On the return movement of the manipulator arm the pivoted finger engages an extension of 120 valve 80^a, and thus returns the control lever 132 to the position shown in Fig. 1, but as the manipulator arm moves from position B to position C, the finger 132^b passes freely 125 past the valve extension 80^a.

Then after the second forging is completed and cut off, the arm while in position E is run forwardly by moving the upper slide forwardly, and the short piece of 5 the blank still in the tongs or jaws is then discharged. Then the arm returns to position A and a new blank is gripped by the jaws or tongs, and the operations are again repeated.

10 When the arm is in positions A and B the axis of the hinge 89 is vertical, but while being moved from position B to position C 15 the arm revolves on its axis through an arc of 90° with the hinge horizontal, and remains in this position until the operation at 20 position D is completed. In other words, when the blank is in the roughing out and finishing dies the hinge is in such position that the arm may swing upwardly in the event the forging sticks to the ascending upper die of the hammer. When the blank 25 is being moved from position D to position E, the arm is turned back to the same position as it occupied when in positions A and B, i. e., with the hinge vertical. This turning or revolving of the arm is, of course, accomplished by the actuation of valve 117.

Both the upper and lower dies of the hammer are each preferably provided with 30 a standard form of vibrator to minimize liability of the blanks sticking to either die, the vibrator attached to the lower die being indicated at 137 in Fig. 2, and the vibrator attached to the upper die being indicated at 138 in the same figure. I may, if desired provide other vibrating means to prevent the forgings sticking to the dies. For example, I may apply a vibrator to the manipulator arm so as to impart a slight 40 vibratory movement to the blank.

It will be understood, of course, that while the forging is being made and the blank is being elongated, the tube automatically shortens, but after the forging is cut off, air 45 is supplied to the brake controlling cylinder 101 so as to allow the arm to assume its normal length before the next foregoing cycle is started.

I provide on the upper carriage an abutment 139 which is designed to strike handle 50 38^a of air valve 38 provided on the frame of the machine as already explained, so as to operate the valve and disengage clutch 35 so as to stop all movements when the arm is 55 in position B and the stock or blank is too short to make a forging. This is provided as an emergency feature to prevent the end of the arm coming under the hammer, and being injured or broken by the upper die.

60 Thus it will be seen that a sequence of operations, in many respects similar to those carried out by the construction of my prior application, is automatically followed out in cycle after cycle, resulting in the forgings being produced one after the other

without any manual control or operation, it being only necessary that there be a supply of blanks fed from the furnace along the delivery trough 12. Should the feed of blanks be stopped for any reason, the machine is thrown out of operation by the engagement of the stop 139 with valve handle 38^a as soon as the arm reaches position B.

Having described my invention, I claim:—

1. In combination with a forging machine 75 having a plurality of separate sets of dies and a delivery member for heated blanks arranged adjacent the front of the forging machine, and a machine for receiving the blanks one at a time from the delivery member and moving them successively into and from the different sets of dies of the forging machine comprising a movable manipulator arm having blank holding means, movable supports for the arm whereby movements in 80 different lineal directions are given to the arm, power means for the arm supports, and automatic controlling means supported independently of the arm supports for controlling the movements of the arm and of 85 the forging machine.

2. In combination with a forging machine having a plurality of separate sets of dies and a furnace having delivery means for heated blanks arranged adjacent the front 95 of the forging machine, an automatic machine for receiving the blanks one after the other, for moving them to and into and out of the different sets of dies of the forging machine and for controlling the latter, said 100 machine including a manipulator arm having blank holding means, and movable supports for the arm whereby movements in different lineal directions are given thereto, power means for shifting the arm supports, 105 power means for operating the forging machine, and automatic control mechanism supported independently of the arm supports for controlling the said power means and for causing repeated cycles of predetermined 110 movements of the arm and operations of the forging machine.

3. In combination with a forging hammer having a plurality of separate sets of dies, a furnace for heating blanks to be forged, a 115 heated blank delivery member extending forwardly past a portion of the hammer for delivering blanks in a line at substantially right angles to and adjacent the front of the hammer, and a manipulator for receiving the blanks and for successively moving them between the sets of dies of the hammer, said manipulator being located in front of the hammer and comprising an arm which extends toward the hammer and is provided with blank receiving means, said arm having supports by which the arm may be moved laterally in front of the hammer and forwardly and rearwardly toward and from the 120 125 130 135

same to successively position the blanks in the different sets of dies.

4. In combination with a machine having a plurality of separate sets of dies for forging blanks and an apparatus for heating blanks having means for discharging the heated blanks at a point substantially in line with the front of the machine, a manipulator having means for grasping the heated blanks one at a time and means for automatically moving said manipulator through a plurality of lineal movements angularly disposed in direction with respect to each other to transfer the blanks from the heating apparatus to the machine and successively move the same into and out of the different sets of dies.

In testimony whereof, I hereunto affix my signature.

20 LOUIS W. GREVE.
